UNITED STATES PATENT OFFICE.

CHARLES A. HERMANN, OF CHICAGO, ILLINOIS.

FEED-BAG FOR HORSES.

1,202,187.

Specification of Letters Patent. Patented Oct. 24, 1916.

Application filed January 24, 1916. Serial No. 73,909.

To all whom it may concern:

Be it known that I, CHARLES A. HERMANN, a citizen of the United States, residing at Chicago, in the county of Cook and State of Illinois, have invented certain new and useful Improvements in Feed-Bags for Horses, of which the following is a specification.

This invention relates to a feed bag for 10 horses, or other draft animals, one object of the invention being the provision of a novel construction of feed bag and support therefor, whereby the horse's head is free to eat comfortably and whereby the waste 15 occasioned in horses tossing their heads to secure the feed at the bottom of the bag is avoided.

A further object of the present invention is the provision of a feed bag that is quickly 20 placed into and out of use, the same being supported from the body instead of the head of the horse, so that the mouth of the horse may have free access to the contents of the bag or receptacle.

25 A still further object of the present invention is the provision of a bag that may be readily supported from the harness, the bag being removably mounted so as to be disposed below the horse's nose in front of 30 his chest.

In the accompanying drawings:—Figure 1 is a perspective view of the feed bag as 35 in use. Fig. 2 is a side elevation of the bag folded. Fig. 3 is an end elevation of the bag folded.

Referring to the drawings, the numeral 5 designates the metal rods, each of which carries at one end a clamping device 6, for engagement with the band 7, that surrounds 40 the body of the animal just to the rear of the front legs. This rod 5 is also provided with a loop or eye 8, to which is adjustably attached the end of a neck strap 9, by means 45 of which the two rods 5 can be supported with their free ends projected forwardly of and at each side of the chest. A loose eye or loop 10 is supported from the underside of the rod intermediate of the clamping device 6 and the loop 8, and the purpose of 50 which will presently appear.

The plates 11 are pivoted at 12 to wings 13 formed on the rods 5 at their free ends so that the rods can readily swing to the position shown in Fig. 2 of the drawing

when said rods 5 are detached from the bands 7. The rods 5 are swung into the position as shown in Fig. 2 of the drawing for the folding thereof and on the extending of the rods the wings 13 will serve as bearings for the plates 11 and thus strengthen the same for supporting the feed bag B.

Affixed to the plates 11 are resilient latches 13' which serve to engage the rods 5 to hold the same locked in extended position 65 as is clearly shown in Fig. 1 of the drawing.

The plates 11 are connected by rivets 14 to the sections 15 and 16 of the metal hinged frame 17, which in turn has connected thereto the edges of the canvas 18 of the bag, the 70 bottom 19 thereof being made of galvanized metal and secured by rivets 20 to the lower edge of the canvas, while the extreme lower ends 23 are of leather.

Carried by the frame 17 is a flexible loop 75 or strap 21, which when the bag is folded as shown in Figs. 2 and 3, surrounds the rods 5 and maintains the parts in folded or collapsed relation.

By means of the clamps 6, the present 80 device may be attached either as shown in Fig. 1, or it may be supported from the traces, breast strap or the girdle of a saddle, or in fact in any manner that will humanely dispose the bag B below the mouth of the 85 horse, so as to permit of natural movement of the neck and head during eating.

To relieve the strain upon the canvas 18 and also to assist in holding the frame 17 either open or closed, the springs 22 are employed. Although they are shown as placed upon the interior of the bag and frame, I 90 do not limit myself to this arrangement.

By providing the loose loop 10, the rods 5 may be connected fixedly to other parts 95 of the harness.

From the foregoing description, it is evident that a humane horse feeding bag is provided, and as the bag may be folded, as shown in Figs. 2 and 3, the midday feed 100 may be placed therein and carried until feeding time.

What I claim, as new, is:—

The combination with a feed bag having a sectional hinged mouth frame, of plates 105 affixed to the sections of said frame at opposite sides of the axis of their hinged connection, supporting rods having hooked ends,

wings formed on said supporting rods and pivotally connected to the plates for folding and unfolding movements of said rods, means detachably engaged in the hook ends 5 of the rods and also engaged with said rods for the mounting of the same upon an animal, resilient latches carried by the plates

and engageable with the rods for holding the same unfolded and extended and means 10 interiorly of the bag and engaged with sections of the mouth frame to hold the same in open position.

In testimony whereof I affix my signature.
CHARLES A. HERMANN.
